UNITED STATES PATENT OFFICE.

GEORGE W. GILLETTE, OF CLEVELAND, OHIO.

LAMP.

1,214,452.

Specification of Letters Patent. Patented Jan. 30, 1917.

Application filed May 27, 1915. Serial No. 30,747.

To all whom it may concern:

Be it known that I, GEORGE W. GILLETTE, a citizen of the United States, residing at Cleveland, in the county of Cuyahoga and 5 State of Ohio, have invented certain new and useful Improvements in Lamps, of which the following is a specification.

This invention relates generally to lamps, and particularly to that class of such devices which are utilized for search-lights 10 and extensive illumination.

More specifically the invention relates to a casing provided with a reflector and a lamp holder having a lamp, the holder being adjustable on the axis of the reflector for obtaining the focus, and also adjustable above and below the axis for the deflection 15 of the light either upward or downward.

The invention may be further briefly summarized as consisting in the construction 20 and combination of parts hereinafter set forth in the following description, drawings and claims.

Referring to the drawings, Figure 1 is a 25 view in side elevation and section showing the device; and Fig. 2 is a view of a lower portion in front elevation showing the means for adjusting.

In carrying out the invention any type 30 of casing and reflector may be utilized so long as they possess the necessary characteristics, but I have shown one embodiment in the drawings, and in this arrangement 1 represents a suitable framework which supports a main casing 2 provided with a reflector casing 3. This casing 3 is provided 35 with the usual door 4 receiving the usual glass front 5. Within the reflector casing 3 is a reflector 6, and this reflector is provided with a suitable bolt 7 and nut 8 at the 40 center for holding it in place within the reflector casing. The reflector 6 is cut away or slotted at 9 for receiving the lamp, as will appear, and this opening aligns with a 45 similar opening 10 in the reflector casing 3.

Mounted upon the underside of the casing 2 is a slide 11 adapted to move from front to rear, in suitable guides 12 secured to the underside of the main casing 2. This slide 50 11 is provided with a downwardly extending lug 13 which receives a threaded shank 14 of an adjusting screw 15 held against

movement of the slide by a bracket 16 secured to the back of the casing 2, a suitable nut 17 being arranged on the inside of the 55 bracket to prevent the backward movement of the screw. The slide is provided with a boss 18 adapted to receive a tubular support 19 carrying a lamp socket 20 at its upper end for the reception of a nitrogen lamp 21. 60 The support 19 is preferably made hollow and receives the wires 22 and is slidable in the boss 18 and the slide 11 is held in any position within the range of its adjustments by the adjusting screw 23. 65

By the arrangement of the parts, it will be seen that the lamp may be moved in and out on the axis of the reflector for obtaining the proper focus and may be raised or lowered within the reflector so as to reflect the 70 light either upward or downward.

Having described my invention, I claim:

1. In a lamp, a stationary frame, a reflector rigidly mounted thereon, horizontal guide-ways on said frame below said reflector and parallel with its axis, a slide movable in said guide-ways, slide adjusting means, and a lamp supporting tube adjustable vertically in said slide and extending through a slot in the lower portion of said 80 reflector. 75

2. In a lamp, a stationary frame, a reflector rigidly mounted thereon and having a longitudinal bottom slot, a casing inclosing and protecting the rear portion of the reflector, said casing having a longitudinal slot in its bottom, guide-ways extending longitudinally of said casing slot outside of said casing and attached thereto, a slide movable in said guide-way, means outside 90 of said casing for adjusting said slide, and a lamp holding tube extending through said slide and said slots from the outside of said casing to the inside of said reflector and adjustable in said slide, and means on the outside of said casing for holding said tube in adjusted position. 95

In testimony whereof I affix my signature in presence of two witnesses.

GEORGE W. GILLETTE.
